Primary Examiner — Rhea Shields(57) **CLAIM**

The ornamental design for a lip makeup brush, as shown and described.

DESCRIPTION

FIG. 1 is a top perspective view of a lip makeup brush;
 FIG. 2 is a bottom perspective view thereof;
 FIG. 3 is a front elevational view thereof;
 FIG. 4 is a rear elevational view thereof;
 FIG. 5 is a right side elevational view thereof;
 FIG. 6 is a left side elevational view thereof;
 FIG. 7 is a top plan view thereof;
 FIG. 8 is a bottom plan view thereof; and,
 FIG. 9 is a detailed view thereof taken about the circle 9-9 seen in FIG. 1.

The broken line showing bristles is included for the purpose of illustrating environmental structure and forms no part of the claimed design.
